UNITED STATES PATENT OFFICE.

WILLIAM W. TRINKS, OF BRIDGEPORT, CONNECTICUT, ASSIGNOR TO FULLCLEAN MANUFACTURING CORPORATION, OF BRIDGEPORT, CONNECTICUT, A CORPORATION OF DELAWARE.

LAUNDERING MACHINE.

Application filed March 29, 1924. Serial No. 702,986.

This invention relates to laundering machines and more particularly to laundering machines of the type disclosed in the pending application Serial No. 516,806, filed November 21, 1921.

The machine of the aforesaid application comprises as its main elements a washing means, a mangle, a feeding means for unwinding a rolled towel supported in advance of the washing means and carrying the same through said washing and mangling means to be operated upon by them in the order named, and a re-winding means for receiving the towel from the feeding means after having been passed through the mangle and automatically re-winding the same into roll form, this entire operation of unwinding, laundering and re-winding the towel being automatically accomplished in one continuous operation.

The mangle of the aforesaid application comprises a plurality of heated drums about which the towel passes for the purpose of being smoothed and dried in usual manner. Encircling these drums are a plurality of laterally spaced bands having on their inner sides a series of inwardly projecting fingers; the function of these devices being two-fold, first, to hold the towels in close contact with the drums when being drawn thereover in order to facilitate drying of the same, and second, to maintain the loose rear ends of the towels in contact with the drums when passing downwardly on the latter, as without these fingers or equivalent holding means the loose rear ends of the towels when brought to such position would have a tendency to drop down and fold on themselves, thus preventing the rear ends of the towels from continuing through the machine in a smooth and unwrinkled condition as it is desirable to have them do. It has been found in practice however that the pressure of the spring fingers of these laterally spaced devices have a tendency to produce score lines on the towels, and in some instances, as when the drums are too hot, to cause the towels to become burned or scorched on the lines engaged by the fingers. Because of this, it has been one of the main objects of the present invention to provide an improved means to perform the function of the said drum en-

circling bands with their attached spring fingers without the objectionable features incident to the use of the latter as referred to. 55

Other objects and advantages of the invention will be referred to during the detailed description of the invention which follows.

Referring now to the accompanying drawings forming part of this specification, in which I have illustrated only so much of a laundering machine as is necessary for the proper illustration of the present invention—

Figure 1 is a sectional side elevation of a two-drum mangle equipped with my improvements, the section being taken on a line just inside of one of the main side frames for the clearer illustration of the parts shown. 70

Fig. 2 is a central vertical section through the upper mangle drum and its directly associated parts.

Fig. 3 is an enlarged detail showing one end of one of the presser rolls and its supporting means. 75

Fig. 4 is a sectional elevation of the rear end of the mangle, on a somewhat larger scale than that shown in Figure 1, and the adjoining mechanism for releasing the towel from the carrier chains, and showing particularly the means for producing slack in the towel in advance of its engagement by the said releasing mechanism. 85

Fig. 5 is a detail in top plan of the said slack producing means.

Similar reference characters indicate like parts in the several figures of the drawings.

The mangle disclosed in the aforesaid application comprised four heating drums, but for the purposes of the present invention I have shown only two, indicated at 102 and 103, corresponding with the like numbered drums of the aforesaid application. These drums are provided with journals 106 and 107 respectively, mounted in suitable journal blocks carried by the side frames or standards 108, 108. 95

Fixed to the opposite ends of each drum are sprocket wheels 110 about which the pair of towel feeding chains 53 pass in carrying the towels around the drums, these sprocket wheels being of substantially the same di-

ameter as that of the drums in order that the towels carried by the feed chains may be held in contact with the drums.

Said drums and their attached sprocket wheels are adapted to be positively driven and this may be accomplished by any suitable means, such, for example, as the means disclosed in the aforesaid application. This comprises an operating cross-shaft 112 having a pinion 116 meshing with a large gear 118 on the upper drum (Fig. 2), which gear 118 in turn meshes with a gear 120 on the lower drum. In this way both drums of the mangle and the towel feeding chains are positively driven in unison.

I will next describe my improved means for holding the towels in contact with the drums. These comprise a series of rollers 10 arranged about the major portion of the circumference of each drum for engagement therewith and each being carried at its opposite ends in lever arms 11, 11, pivoted at 12 on fixed frames 13, 13, adjacent the opposite ends of the drums. These rollers are 25 adapted to yieldingly engage the drums, or the towels passing thereover, and in order to effect this the arms 11 are provided with extensions 14 with which connect one end of coiled pull springs 15, the opposite ends of 30 which latter connect with the fixed frames 13, as clearly shown in the drawings. The rollers 10 being thus supported for yielding engagement with the towels and of a length sufficient to engage the same throughout 35 their full width, have been found to be most efficient for holding the towels in proper drying contact with the drums and without any of the objectionable features incident to the use of the spring fingers heretofore used.

In addition to holding the towels in drying contact with the drums during their passage over the latter as described, these rollers 10 at the sides of the drums where the towels take a downward path—at the front of the upper drum and the rear of the lower drum in the present case—also serve to prevent the loose rear ends of the towels from dropping away from the face of the drying drums as they otherwise would. In case some such provision were not made to so hold the loose rear ends of the towels in contact with the drums, it will be clear that said ends would not be dried to the same extent 50 as the balance of the towels, and also, that they would have a tendency to drop and fold upon themselves and so become wrinkled during their further passage through the machine, as hereinbefore referred to.

The fixed frames 13, 13 upon which the roller carrying arms 11 and associated parts are mounted, may be of any suitable construction. As here shown they are circular in form to conform generally with the ends 55 of the heating drums and are mounted upon

cross-rods of the main supporting frame, the frames 13 associated with the upper drum being carried by cross-rods 16, 17 and the frames 13 associated with the lower drum being carried by the cross-rods 18, 19.

As disclosed in the aforesaid application, the leading end of each towel is adapted to be detachably connected with the feed or carrier chains 53 by means of a bar, shown in section at 20 in Fig. 4, which is passed 75 through a loop in the end of the towel and connected at its opposite ends with said chains. When this bar, termed the "towel bar", has been carried some distance beyond the mangle it is adapted to be released from the carrier chains and transferred to a re-winding mechanism (not shown here). Such release of the towel-bar from the carrier chains is automatically effected by means of releasing or transfer chains 220 80 which are operated at a greater speed than that of the carrier chains in order to release the towel-bar from the latter by a movement in the direction of movement of the feed chains. To do this, it obviously requires a certain amount of slack in the towel adjacent the point where it is taken by the releasing chains from the feed chains. Such slack is provided by deflecting the feed chains downwardly beneath the guide wheels 145 in their passage from the guide wheels 143 to the guide wheels 146, as shown in Fig. 4. To control such slack in the towel and maintain the same under proper tension, I provide a plurality of tension rolls, here shown as three in number and indicated at 25, 26 and 27, for engaging the towel at such point, these rolls being movably supported in order to yield and give off slack under the pulling action of the towel *t*, as shown 90 by dotted lines in Fig. 4, which takes place when the towel-bar is advanced from its connection with the carrier chains by the engagement therewith of the more rapidly moving releasing chains.

The several tension rolls 25, 26 and 27, are carried at their opposite ends by a series of connecting links 30, 31 and 32, the upper ones 30 being pivotally connected with and supported by the ends of the guide 115 wheels 143 (Fig. 4). Said tension rolls, when in normal position, rest upon a stationary supporting bed 35 mounted upon the frame of the machine in a position between the guide wheels 143 and 145. This bed 120 is provided with slots 36 adjacent its opposite edges to receive the guide flanges 37 on the opposite ends of the tension rolls, as clearly shown in Fig. 5, and permit the rolls to rest upon said bed, as shown in Fig. 4.

It has been found in practice that this plurality of tension rolls, pivotally linked together and loosely resting upon the bed 35, provide a means for controlling the slack in the towels much more efficiently than was 125

accomplished by the single tension roll of our aforesaid application; this resulting in part from the fact that it gives a greater and more uniform tension than was provided with the single roll.

5 The releasing chains 220 may be operated at a greater speed than the carrier chains, as and for the purpose above referred to, by any suitable means. Preferably they are so operated by the means shown and described in detail in my aforesaid application Serial No. 516,806; the said releasing chains being in the form of endless sprocket chains mounted on pairs of sprocket wheels 221, 222 and 223, the first two pair being guide wheels and the last pair, 223, being drive wheels mounted on a drive shaft 176. These chains 220 are provided with projections 224 which are moved in paths to engage the ends of the towel bar 20 adjacent the rear end of the upper run of the carrier chains 53, and, by reason of their moving at a greater speed than the carrier chains, will release said bar from the latter.

25 What I claim is:

1. In a machine of the class described, the combination with laundering means, of a continuously moving towel feeding carrier, towel releasing means moving at a greater speed than that of the carrier to release the towel therefrom, and yieldable means operative to produce slack in the towel in advance of its engagement by the releasing means, said yieldable means comprising a plurality of towel-engaging rollers carried by a plurality of pairs of pivotally connected links.

2. In a machine of the class described, the combination with laundering means, of a continuously moving towel feeding carrier, towel releasing means moving at a greater speed than that of the carrier to release the

towel therefrom, and yieldable means operative to produce slack in the towel in advance of its engagement by the releasing means, said yieldable means comprising a 45 plurality of towel-engaging rollers carried by a plurality of pairs of pivotally connected links, and a support with which the rollers loosely engage.

3. In a machine of the class described, 50 the combination with laundering means, of a continuously moving towel feeding carrier, towel releasing means moving at a greater speed than that of the carrier to release the towel therefrom, and yieldable 55 means operative to produce slack in the towel in advance of its engagement by the releasing means, said yieldable means comprising a plurality of towel-engaging rollers carried by a plurality of pairs of pivotally connected links, and a support in the form of a stationary bed with which the rollers loosely engage.

4. In a machine of the class described, 65 the combination with laundering means, of a continuously moving towel feeding carrier, towel releasing means moving at a greater speed than that of the carrier to release the towel therefrom, and yieldable 70 means operative to produce slack in the towel in advance of its engagement by the releasing means, said yieldable means comprising a plurality of towel-engaging rollers carried by a plurality of pairs of pivotally connected links, each of said rollers being provided 75 with guide flanges adjacent their opposite ends, and a supporting table with which the rollers loosely engage having slots to receive the guide flanges on the rollers.

In testimony whereof I affix my signature.

WILLIAM W. TRINKS.
